WEB PRINTING MACHINE

Cecil George Quick, Eltham, London, and Thomas Richard Bennett, Willesden, London, England, assignors to R. Hoe & Co., Inc., New York, N. Y., a corporation of New York; Irving Trust Company, permanent trustee

Application May 4, 1931, Serial No. 534,814
In Great Britain July 7, 1930

10 Claims. (Cl. 101—247)

This invention relates to web printing machines and provides means for moving the cylinders of a printing couple relatively to one another into and out of impression contact, and a clutch device for disconnecting the drive of one of the printing cylinders whereby when it is disconnected from its normal drive, it can be rotated independently by means of a hand wheel or the like.

Preferably means are provided for varying the impression pressure, the means for causing the relative movement of the cylinders into and out of impression contact being such that the impression pressure can be regulated without affecting or being affected by the movement of an operating device for effecting the relative movement.

The invention is illustrated in the accompanying drawings in which Figure 1 is a view taken crosswise of the machine, with the parts shown partly in section and partly broken away;

Figure 2 is a sectional view on the line 2—2 of Figure 1, as seen in the direction of the arrow; and

Figures 3 and 4 are diagrammatic views showing the movable cylinder in and out of impression contact.

A form cylinder is indicated by the numeral 1, and an impression cylinder by the numeral 2, these constituting a printing couple. The cylinder 1 is secured to a shaft 3, journaled preferably in roller or other anti-friction bearings carried in a bore formed eccentrically in bushings 4 that are rotatably mounted in side frames 5.

Rotatably mounted on the bushings 4, are annular members or plates 6, to which are pivotally connected one of the ends of links 7, whose other ends are mounted on crank pins 8, formed on blocks 9, secured to a shaft 10, that is rotatably supported in bearings 11 and capable of being locked in any desired position by a hand nut 12, which is screw threaded on a bolt 12', and the movement of the shaft is limited by a pin 13 on one of the blocks 9, which is adapted to engage abutments formed by cutting away a part of one of the bearings 11.

To the shaft 10, is secured a disc 14, having V shaped teeth formed in its periphery, and a pawl 15 is pivotally mounted on an operating hand lever 16, freely mounted on the shaft 10. A pin 17 is provided to support the lever 16 in an out of use position, and the pawl is arranged so that it can be turned from one side of the lever 16 to the other in order to rotate the disc 14 in one direction or the other.

To the plates 6 are secured bearings 18, on

which are mounted shafts 19, formed with worms 20 in mesh with teeth formed on sectors 21, secured to flanges on collars 21' that are secured to the bushings 4, the shafts 19 being formed with squared ends for the reception of a tool such as a box wrench.

Rotatably mounted on the shaft 3 is a gear wheel 22, in mesh with a gear wheel on the impression cylinder 2, the gear wheels being driven in any convenient manner from the main drive of the printing machine. The gear wheel 22 is formed with an aperture which is adapted to receive a pin 23, on a clutch member 24, slidably but non-rotatably mounted on the shaft 3, the member being provided with a circumferential groove into which extends a block 25, pivotally mounted on a crank pin 26, that is secured to a flange 27, formed on a spindle 27' to which an operating hand lever 28 is secured. The friction drag exerted between the block 25 and the walls of the circumferential groove tend to maintain the lever 28 in one extreme position against a stop which is constituted by an abutment in a bearing for the spindle 27'. A pin 29 is carried by the flange 27 that is formed on the spindle 27', and carries the pin 26 on which the block 25 is mounted.

One end of the shaft 3 is provided with a hand wheel 30, by means of which the cylinder 1 can be rotated by hand when the clutch is disengaged.

The plates on the printing cylinder 1 are supplied with ink from a drum 31 through form rollers 32, 33.

In operation if it is desired to change the plates on the cylinder 1, the drive to the cylinder is first disconnected by rocking the hand lever 28, to cause the pins 23 to withdraw from the apertures in the gear wheel 22.

The hand nut 12 being released, the lever 16 is then rocked, whereby the pawl 15 in one direction of its movement, engages the V teeth in the disc 14 and drives this latter, and hence the shaft 10, until the pin 13 engages one of the abutments, the pawl riding idly over the disc in the other direction of movement of the lever. The partial rotation of the shaft 10 is transmitted through the links 7, to the plates 6 and thus the collars 21' and the bushings 4 are rotated. The printing cylinder 1 is thereby moved away from the impression cylinder 2, and the form rollers 32 and 33, and can now be rotated independently of the rest of the machine by the hand wheel 30 to effect, for example, the changing of the plates.

When it is desired to move the cylinder 1 into

impression contact with the cylinder 2, the pawl 15 is swung to the other side of the lever 16 and hence the disc 14, the shaft 18 and the bushings 4 are rotated in the opposite direction until the pin 13 engages with the other abutment. The drive to the cylinder is again connected by rocking the hand lever 28 to cause the pin 23 to enter the aperture of the gear wheel 22.

If it is desired to adjust the impression pressure, this can be effected by rotating the worm shaft 19, which rocks the sector 21 and hence varies the position of the eccentric with respect to the plate 6. Thus, the plate being movable between the fixed limits constituted by the pin and abutments, the impression pressure is unaffected by the movement of the cylinder 1, into and out of impression contact with the cylinder 2.

It will be seen that the pin 13 and cooperating abutments permit the shaft 18 to move through 180°, and that in each extreme position of the shaft, the line of thrust in each of the links 7, passes through or substantially through the axis of the shaft. By this means, the shaft 18 and links tend to remain in their extreme positions automatically although as has been set out, the hand nut 12 is provided to lock the shaft in the printing position of the printing cylinder.

In addition to moving the printing cylinder 1 out of contact with the form rollers 32, 33, the form rollers may themselves be moved out of contact with the drum 31, in any convenient manner, the out of contact position of the cylinder and rolls being shown in Figure 4.

What we claim is:

1. In a printing machine, a frame, a printing couple comprising a printing cylinder and an impression cylinder, bearings for the cylinders, an eccentric device for each bearing of one of the cylinders adapted to move the said cylinder relative to the frame and transversely to the axis of the other cylinder, a member operably connected to each eccentric and limitedly rotatable with respect thereto, means for separately adjusting each eccentric relative to its connected member to vary impression pressure, means for rotating both of said members simultaneously to move the movable cylinder out of impression relation with the other cylinder, a driving gear for the movable cylinder, and a clutch device for disconnecting the gear from the cylinder.

2. In a printing machine, a frame, a printing couple comprising a printing cylinder and an impression cylinder, bearings for the cylinders, an eccentric device for each bearing of one of the cylinders adapted to move the said cylinder relative to the frame and transversely to the axis of the other cylinder, a gear segment on each eccentric device, a member operably connected to each eccentric by a worm rotatably supported on said member, means for separately adjusting each eccentric relative to its connected member to vary impression pressure, means for rotating both of said members simultaneously to move the movable cylinder out of impression contact with the other cylinder, a driving gear for the movable cylinder, and a clutch device for disconnecting the gear from the cylinder.

3. In a printing machine, a printing couple comprising a printing cylinder and an impression cylinder, bearings rotatably supporting the cylinders, a pair of annular members rotatable about the bearings, a pair of eccentrics operably connected to the annular members and adapted to move one of the cylinders transversely to the axis of the other cylinder, means for separately ad-

justing each eccentric relatively to one of the said members to vary impression pressure, and means for moving both annular members simultaneously to move the movable cylinder out of impression relation with the other cylinder, said last-mentioned means including a manually operable member freely rotatable on means connected to the annular members, and instrumentalities for operatively engaging the manually operable member with the last-mentioned means.

4. In a printing machine, a printing couple comprising a printing cylinder and an impression cylinder, a driving member for the printing cylinder, bearings rotatably supporting the cylinders, a pair of annular members rotatable about the bearings, a pair of eccentrics operably connected to the annular members and adapted to move one of the cylinders transversely to the axis of the other cylinder, means for separately adjusting each eccentric relatively to one of the annular members to vary impression pressure, means for moving both annular members simultaneously to move the movable cylinders out of impression relation with the other cylinders, and a clutch device for disconnecting the driving member from the printing cylinder.

5. In a printing machine, a printing couple comprising a printing cylinder and an impression cylinder, bearings rotatably supporting the cylinders, a pair of annular members rotatable about the bearings, a pair of eccentrics operably connected to the annular members and adapted to move one of the cylinders transversely to the axis of the other cylinder, a gear segment on each eccentric and a worm rotatably mounted on each annular member whereby when the said members are held in fixed position impression pressure may be adjusted by turning the worms, means for moving both annular members simultaneously to move the movable cylinder out of impression relation with the other cylinder, said last-mentioned means including a shaft, links connecting said shaft and annular members, a ratchet on said shaft, and a manually operable member having a pawl engaging said ratchet.

6. In a printing machine, a printing couple comprising a printing cylinder and an impression cylinder, a driving member for the printing cylinder, bearings rotatably supporting the cylinders, a pair of annular members rotatable about the bearings, a pair of eccentrics operably connected to the annular members and adapted to move the printing cylinder transversely to the axis of the impression cylinder, a gear segment on each eccentric and a worm rotatably mounted on each annular member whereby when the said members are held in fixed position impression pressure may be adjusted by turning the worms, means for moving both annular members simultaneously to move the printing cylinder out of impression relation with the impression cylinder, and a clutch device for disconnecting the driving means from the printing cylinder.

7. In a printing machine, a frame having aligned apertures formed therein, a printing couple including a printing cylinder and an impression cylinder, spaced bearings for each cylinder, spaced eccentric members supporting the bearings for one of the cylinders, each eccentric member being rotatably mounted directly in one of the said frame apertures, an annular member operably supported by each eccentric member and movable relative thereto, means operably interposed between each eccentric member and annular member for limitedly rotating each ec-

5 centric member relative to its annular member to thereby vary the impression pressure between the cylinders and for locking each eccentric member to its annular member, and means for limitedly rotating each annular member thereby rotating the eccentric member and the annular members in unison to move one of the cylinders out of impression relation with the other cylinder.

8. In a printing machine, a frame having alined 10 apertures formed therein, a printing couple including a printing cylinder and an impression cylinder, spaced bearings for each cylinder, spaced eccentric members supporting the bearings for one of the cylinders, each eccentric member being rotatably mounted directly in one of the said frame apertures, an annular member operably supported by each eccentric member, a worm and segment operably interposed between each eccentric member and annular member for limitedly rotating each eccentric member relative to its annular member for varying the impression pressure between the cylinders and for locking the eccentric member and its rotatable member against relative rotary motion, and means for imparting limited rotation to each 20 annular member thereby limitedly rotating the eccentric member and the annular members in unison to move one of the cylinders out of impression relation with the other cylinder.

30 9. In a printing machine, a frame having alined apertures formed therein, a printing couple including a printing cylinder and an impression cylinder, spaced bearings for each cylinder, spaced eccentric members supporting the bearings for one of the cylinders, each eccentric member being rotatably mounted directly in one of the 35 said frame apertures, an annular member operably supported by each eccentric member, means operably interposed between each eccentric member and its annular member for locking each eccentric member to its annular member and operable to limitedly rotate the eccentric member relative to the annular member to vary the impression pressure between the cylinders, a common rotatable shaft operably connected to each annular member for limitedly rotating each 30 annular member and its eccentric member as a unit to thereby move one of the cylinders out of impression relation to the other cylinder, bearings for operably supporting the said rotatable shaft, and means for clamping one of the bearings to 35 the shaft to lock the shaft against rotation thereby locking the cylinder in impression relation.

tric member and its annular member for locking each eccentric member to its annular member and operable to limitedly rotate the eccentric member relative to the annular member to vary the impression pressure between the cylinders, 5 common movable means for limitedly rotating the annular members thereby rotating an annular member and eccentric member as a unit to move one of the cylinders out of impression relation to the other cylinder, and means for locking the 10 said common movable means against movement to thereby lock the cylinders in impression relation.

10. In a printing machine, a frame having alined apertures formed therein, a printing couple 15 including a printing cylinder and an impression cylinder, spaced bearings for each cylinder, spaced eccentric members supporting the bearings for one of the cylinders, each eccentric member being rotatably mounted directly in one of 20 the said frame apertures, an annular member operably supported by each eccentric member, means operably interposed between each eccentric member and its annular member for locking each eccentric member to its annular member 25 and operable to limitedly rotate the eccentric member relative to the annular member to vary the impression pressure between the cylinders, a common rotatable shaft operably connected to each annular member for limitedly rotating each 30 annular member and its eccentric member as a unit to thereby move one of the cylinders out of impression relation to the other cylinder, bearings for operably supporting the said rotatable shaft, and means for clamping one of the bearings to 35 the shaft to lock the shaft against rotation thereby locking the cylinder in impression relation.

CECIL GEORGE QUICK.

THOMAS RICHARD BENNETT.
